CLAIM

The ornamental design for a nasal spray device, as shown and described.

DESCRIPTION

1.1 is a front view of a nasal spray device showing our new design; the back view is identical;

1.2 is a top perspective view thereof;

1.3 is a right side view thereof; the left side view is identical;

1.4 is a top view thereof;

1.5 is a bottom view thereof; and

1.6 is a bottom perspective view thereof.

The shorter dashed broken lines represent portions of the article that form no part of the claimed design. The longer dashed broken lines represent changes in the slope of a surface and the lines form no part of the claimed design.

1 Claim, 6 Drawing Sheets
